SMOKER'S PIPE WITH A CLEANER
THEREFOR

Frederick E. Boehm, Fulton County, Ohio

Application October 17, 1944, Serial No. 559,010

1. Claim. (Cl. 131—184)

1 This invention relates to loosening and thrusting detritus from the passage of smokers' pipes.

This invention has utility when incorporated as an accessory for a bowl-stem and mouth-piece type of a smoker's pipe, wherein a scraper for the passage from the bowl may thrust detritus clear of the mouthpiece.

Referring to the drawings:

Fig. 1 is a side elevation, with parts broken away, of a tobacco smoker's pipe, having the accessory of the invention incorporated therewith;

Fig. 2 is an enlarged view, in section, of the bowl region of a smoker's pipe, with the accessory operating head disconnected and clear of the bowl and the accessory scraper not shown;

Fig. 3 is a detail view, in section, of a mouth-piece for a pipe, approximating the scale of Fig. 2, and with the scraper partially broken away but connected for actuation by the rod to thrust detritus for its discharge at the mouth piece port;

Fig. 4 shows a fragment, in section, of a smoker's pipe bowl in which the scraper from Fig. 3 is in the vicinity of the bowl;

Fig. 5 is a longitudinal section of the tubular scraper with its mounting on the rod and seat or connector;

Fig. 6 is a section on the line VI—VI, Fig. 5, looking in the direction of the arrow, showing the scraper inactive end half in elevation;

Fig. 7 is a detail view of the bowl-anchored sleeve further enlarged over the showing thereof in Fig. 2;

Fig. 8 is a section from the line VIII—VIII, Fig. 7, looking in the direction of the arrow;

Fig. 9 is an end elevation on an enlarged scale from the left of the head in Fig. 2;

Fig. 10 is a plan view of the scraper cylinder; and

Fig. 11 is a section of the mouth-piece portion of a pipe at smoking assembly therefor, the scraper being absent therefrom.

From a pipe bowl 1, there is shown a projecting portion 2 having an interfitting connection 3 with a stem extension 4 to a mouthpiece 5. The bowl 1 has a chamber 6 to receive a charge of tobacco to be smoked. A base portion 7 from the bowl 1 has a draft passage 8 thru the portions 2, 4, and the mouth-piece 5 to a port 9. In alignment with the passage 8 as remote from the port 9, there is a sleeve 10 thru the wall of the bowl 1 to the bottom of the chamber 6. Intermediate its length, the sleeve or seating means 10 has an internally threaded portion 11 in which is positioned a bushing 12. There is thus pro-

vided in the sleeve 10 on the side of the bushing 12 away from the chamber 6, a chamber 13.

A head 14 of a cleaner actuator is mounted on a slender rod or wire 15. Centrally thru the bushing 12 is an opening 16 providing a guideway for the rod 15. Upon seating the head 14 in the chamber 13, the rod 15 from the head 14 extends thru the passage 8 into proximity of the port 9. The end of the rod 15 remote from

10 the head 14 has an enlargement seat or connector portion 17, herein shown as having an externally threaded region. The portion 17 has a tapering prong portion 21 for clearing debris.

A key portion 18 on the head 14 coacts with 15 a complementary seat portion 19 at the top of the chamber 13. With the head 14 seated in the chamber 13, finger nail notches 20 are accessible for the pipe user to withdraw the head from its 20 seat, wherein it is approximately flush with the pipe bowl exterior.

A cylinder member 21 (Figs. 3, 5, 6) has a scraper end 22 and remote therefrom, an internal seat or threaded portion 23 complementary to the threaded region seat or connector portion 17.

25 This assembly provides a detachable connection.

The scraper cylinder 21 is positionable in the region of the bottom of the pipe bowl chamber 6. With the seat 17 disconnected from the scraper cylinder 21, the rod 15 may protrude from the cylinder 21 and extend along the passage 8. The 30 disconnection of the cylinder 21 is brought about by bringing the projecting means 25 which are at the rear end of the cylinder 21 into engagement with complementary seats 26, forming radially extending notches in the bushing 12 (Figs. 2, 7). The key head 14 from the rod 15 is a guide

35 for the operator in turning the rod 15 to bring the parts 25, 26, into register, but also for checking the limit for withdrawal of the rod 15. Now by turning the rod 15, there may be disconnection between the portions 17, 23, to leave the cylinder 21 lodged in the sleeve 10 while the rod may be moved along the passage 8 toward the mouth-piece 9. In this movement of the portions 17

40 and 21 from the cylinder 21, such detritus as fragment 28 that may be there lodged or be along the passage 8, may be spilled from the mouth-piece 9, if not shaken from the bowl chamber 6. The waste matter discharged from the mouth-piece is shown at 24 in Fig. 3.

When the pipe is used for smoking, the scraper cylinder 21, 22 is in retracted position within the sleeve 10; the projecting means 25 being engaged with the seats 26 of the bushing 12. The 45 rod 15 is positioned in the passage 8 with the

head 14 in the chamber 13, and the connector portion 17 in the mouthpiece, as seen in Figs. 1 and 11. The smoke would pass from the bowl, through the passage 8, past the portion 27 and out through the port 9.

For cleaning the pipe, the head 14 is withdrawn from the chamber 13, and the rod 15 retracted until the threaded connector portion 17 engages with the threaded portion 23 of the cylinder 21, positioned in the sleeve 10. Portions 17 and 23 are then screwed together. Then rod 15 with portion 17 is moved forwardly, carrying the scraper cylinder 21 thereon towards the mouthpiece as seen in Fig. 3. The scraper end 22 of the cylinder 21 thus cleans the passage 8 of debris.

After cleaning, the cylinder 21 is retracted and positioned within the sleeve 10, the projecting means 25 engaging with the seats 26 of the bushing 12 as stated above. The rod 15 with its threaded portion 17 is then unscrewed from the threaded portion 23 of the cylinder 21, and the rod 15 with its portion 17 moved forwardly to position the portion 17 in the mouthpiece (Fig. 11) as stated above. During this movement, the prong portion 27 cleans the cylinder 21 and passage 8 of waste matter that may remain.

Due to the fact that the general external contour may be retained for the pipe structure, the whims of various smokers may be taken care of thru the incorporation of the disclosure herein as an accessory or conversion means.

What is claimed and it is desired to secure by Letters Patent is:

In a smoker's pipe comprising a bowl provided with an opening in the bottom thereof, a portion projecting from the bowl, a stem, and a mouthpiece having an end port, said projecting portion and stem having a smoke passage extending from the bowl to the mouth-piece port and of approximately constant diameter throughout, a pipe cleaner comprising a rod having a head at one

end and a connector portion at the other end, said connector portion being spaced radially from the passage wall at all times, the opening in the bowl adapted to be closed by said head; a scraper 5 movable within the smoke passage and having an opening thru which the rod extends, said scraper having a connector portion complementary to the connector portion of the rod; a sleeve having a bushing therein positioned in the bowl opening, said scraper adapted to be positioned either in said mouth-piece or sleeve, and co-acting means between said scraper and bushing to prevent relative rotation between them to permit the connector portion of the rod to be connected to or disconnected from said scraper; said rod and scraper being operable by said head to thrust the scraper from the sleeve, past the bowl and thru the projecting portion and stem to a flush position with the mouth-piece port for cleaning the smoke passage of debris; said scraper being positionable within said sleeve, and said connector portion of the rod being positionable in proximity to said mouth-piece when the pipe is being used for smoking.

FREDERICK E. BOEHM.
